UNITED STATES PATENT OFFICE.

JOSEPH HAJEK, OF FOLLANSBEE, WEST VIRGINIA.

SHOE.

1,417,517.

Specification of Letters Patent. Patented May 30, 1922.

Application filed August 5, 1919. Serial No. 315,479.

To all whom it may concern:

Be it known that I, JOSEPH HAJEK, a citizen of Czechoslovakia Republic, residing in the town of Follansbee, in the county of Brooke and State of West Virginia, have invented new and useful Improvements in Shoes, of which the following is a specification.

This invention relates to improvements in 10 shoes and has for its object to provide a shoe which will keep the feet of the wearer thoroughly ventilated.

Another object of the invention is to provide a shoe having means for admitting a 15 plentiful supply of atmospheric air to the feet of the wearer without admitting water into the shoe.

A still further object of the invention is to so construct a shoe that the vapors generated 20 through perspiration of the feet will be carried off from the shoe and fresh air constantly admitted thereinto whereby the feet of the wearer will be kept in a dry and healthful state.

With these and other objects in view my 25 invention consists in the novel construction, combination and relative position of the parts and members hereinafter described and shown in the accompanying drawings, 30 and particularly pointed out in the appended claims.

Referring to the drawing in which like reference characters indicate like or corresponding parts:

Figure 1 is an elevational view of my improved shoe.

Figure 2 is a top plan view thereof.

Figure 3 is a vertical sectional view of the shoe.

Figure 4 is a plan view of sole the upper and insole being removed.

Figure 5 is a plan view of a toe box.

Figure 6 is an end view thereof.

Figure 7 is a section on line 7—7 Figure 45 4, and

Figure 8 is a fragmental view of an insole.

In the several views in the drawings, 1 is my improved hygienic ventilating shoe, 50 which in general appearance is similar to the ordinary walking shoe and can be made in any particular formation desired. Among the principal features of my invention are the perforated toe box 2, and the 55 perforated insole 3 and means for causing

a circulation of air to be forced constantly through said perforations and directly to the feet of the wearer.

Located between the slip sole 4 and insole 3 is a series of preferably thin main flexible 60 tubes 5, 6 and 7 and a branch tube 8 which extend from heel 9 to toe 10 and branch off at the forward end of the shoe so that the forward ends 11, 12, 13 and 14 of said tubes are positioned between the toes of the wearer, as indicated in Figure 4. These tubes are formed preferably of fine coil wire 15 with coverings 16 as indicated in Figure 7. The weight of the wearer in walking upon these tubes causes an alternate expansion 65 and contraction thereof whereby air will be alternately drawn in and forced out to afford a continual passage of air into and out of the shoe. The tubes 5, 6 and 7 at their rear ends project through openings in the 70 counter 17 and vamp 18 and are bent upwardly to form vertical extensions 19, 20 and 21 which run up to the top edge 22 at the back of the shoe from whence air passes in and out of said tubes. In tubes 19 and 21 80 are located check valves 23 arranged to check any outflow of air, but to permit an inflow while in tube 20 a check valve 24 permits the outflow of air but prevents inflow thereof. It will be seen that fresh air is 85 constantly being pumped in through tubes 19 and 21 which, after circulating around in the shoe is forced out through tube 20. The upper surfaces of the tubes 5, 6 and 7 are provided with suitably spaced perforations 90 25 so that the air may pass in and out of the tubes at suitable points within the shoe.

The toe box 2 is provided with a series of longitudinal grooves 26 extending at 95 spaced intervals entirely thereacross; all of said grooves being perforated at suitable intervals as at 27. All grooves 26 run into a transverse channel 28, to which are connected tubes 29 and 30, which are located 100 between the vamp 31 and its lining 32 and which extend to the upper edge 33 of the front of the shoe. These tubes are formed similar to tubes 5, 6 and 7 and have perforations 34 through which air passes into and 105 out of the shoe. These latter tubes may be made of soft rubber if desired. Air passes from these tubes to channel 28 and from thence through channels 26 and perforations 27 to the toes of the wearer. The toe box is 110

covered by a cap 35. Valves may or may not be used in tubes 29 and 30 as found most expedient. The tubular extensions 19, 20 and 21 are enclosed in a leather covering 36.

5 I claim:

1. In a shoe, means for forcing a circulation of air thereinto, said means including a series of tubes, said tubes being perforated at intervals, and means for distributing said 10 air in the shoe, said last means consisting of a grooved toe box, the grooves of which are perforated, certain of said tubes being located between the slip sole and insole of the shoe, certain other of said tubes being 15 located against the vamp of the shoe, and within the lining of the vamp, said tubes being flexible, whereby pressure thereon will cause them to pump air, valves located in said tubes, certain of which permit ingress 20 and prevent egress of air therethrough.

2. In a shoe, means for forcing a circulation of air thereinto, said means including a series of tubes, said tubes being perforated at intervals, and means for distributing said air in the shoe, said last means consisting of 25 a grooved toe box the grooves of which are perforated, certain of said tubes being located between the slip sole and insole of the shoe, certain other of said tubes being located against the vamp of the shoe, and 30 within the lining of the vamp, said tubes being flexible, whereby pressure thereon will cause them to pump air, valves located in said tubes, certain of which permit ingress 35 and prevent egress of air therethrough, and certain others of which permit egress and prevent ingress of air therethrough.

In witness whereof, I have hereunto subscribed my name this 28th day of July, 1919.

JOSEPH HAJEK.
